DESIGN FOR A STATIONERY CASE

George B. Walters, New York, N. Y.

Application June 27, 1941, Serial No. 101,747

Term of patent 3½ years

To all whom it may concern:

Be it known that I, George B. Walters, a citizen of the United States and resident of New York city, in the county of New York and State of New York, have invented a new, original, and ornamental Design for a Stationery Case, of which the following is a specification, reference being had to the accompanying drawing, forming a part thereof.

In the drawing:

Fig. 1 is a perspective view of a stationery case in folded condition, showing my new design,

Fig. 2 is a perspective view of the same in open position.

Fig. 3 is another view similar to Fig. 2, illustrating all the covers in open condition.

Fig. 4 is a side elevational view of Fig. 2.

I claim:

The ornamental design for a stationery case, as shown.

GEORGE B. WALTERS.
